UNITED STATES PATENT OFFICE.

FREDERIC H. BENDER, OF CHICAGO, ILLINOIS, ASSIGNOR TO AMERICAN STEEL
FOUNDRIES, OF CHICAGO, ILLINOIS, A CORPORATION OF NEW JERSEY.

TRUCK-PEDESTAL.

1,275,644.

Specification of Letters Patent. Patented Aug. 13, 1918.

Application filed June 18, 1917. Serial No. 175,404.

To all whom it may concern:

Be it known that I, FREDERIC H. BENDER, a citizen of the United States, and resident of Chicago, in the county of Cook and State 5 of Illinois, have invented certain new and useful Improvements in Truck-Pedestals, of which the following is a specification.

This invention relates to car truck pedestals, and has particular reference to novel 10 uniting means for the lower ends of the pedestal jaws, and is an improvement upon the arrangement disclosed in the Hedgcock Patent No. 1,157,867, granted October 26, 1915.

15 In the patent referred to the opening between the jaws is closed by a tie strap and also a bar, the tie strap resting upon the bar and being located between the bar and portions of the jaws, dowel pins formed on 20 the bar extending upwardly through openings in the tie strap and into openings formed in the jaw members. It has been found that the tie strap vibrates considerably on the bar or binder, thereby causing 25 the pins to wear excessively. The assembling of the parts of the arrangement disclosed in the mentioned patent also may be improved.

The invention is illustrated on the accompanying sheet of drawings in which,

Figure 1 is a side elevation, parts being in section of a pedestal embodying my invention;

Fig. 2 is a sectional view taken in the planes of line 2—2 of Fig. 1, and,

Fig. 3 is a fragmentary side elevation of the pedestal.

The various novel features of my invention will be apparent from the following 40 description and drawings, and will be particularly pointed out in the appended claims.

The pedestal includes an upper horizontally arranged member 10 having depending therefrom oppositely arranged jaws 11 and 12 provided with a lining 13. The lower ends of the jaws are united, or the opening between the jaws is closed by a binder or bar 14 and a tie strap 15. The 45 tie strap is secured to the lower ends of the jaws 11 and 12 between oppositely arranged depending projections 16 and 17 on each jaw, bolts 18 passing through registering

openings in the jaws 11 and 12 and in the tie strap 15. Nuts 19 are applied to the 55 bolts to rigidly hold the tie straps in contact with the jaws. The binder or bar 14 has arranged on opposite ends thereof recessed portions forming ears 20 provided with openings 21 which register with openings 22 formed in the jaw projections 16, 17, and which receive removable pins 23 for securing the binder or bar 14 to the jaws 11, 12. It will be noted that the tie strap 15 and the bar 14 are secured to the 65 jaws 11 and 12 independently of each other and that the tie strap is located over and out of engagement with the bar 14. Any vibrations which may be set up in the tie strap will in no wise effect the bar 14 or its connections with the jaws 11 and 12. It will be noted also that the tie strap is first secured to the jaws, and then the bar 14 is secured thereto with the ears 20 at the ends of the bar 14, straddling the nuts 19 to lock 70 the same against movement. It is apparent therefore that there is no possibility for the tie strap becoming accidentally loosened from the jaws. Furthermore, the pins 23 are locked in their operative positions by 75 conveniently located cotter pins 24 which pass through apertured laterally extending portions 25 and 26 formed on the jaws 11 and 12. It will be noted that the cotter pins 24 do not pass through pins 23, but are 80 arranged adjacent the heads of the pins 23 to prevent accidental removal thereof.

It is apparent that there may be modifications of the invention herein particularly shown and described, and it is my intention 90 to cover all such modifications which do not involve a departure from the spirit and scope of the invention as set forth in the following claims.

I claim:

1. A car truck pedestal including associated jaws with spaced projections, a tie strap and a bar mounted between said projections serving to close the opening between the jaws, said tie strap and bar being 100 secured to said jaws independently of each other.

2. A car truck pedestal including associated jaws, a tie strap closing the openings between said jaws, means for securing the 105 tie strap to the jaws, and a bar extending

between and secured to said jaws forming a lock for the tie strap securing means.

3. A car truck pedestal including depending jaws, a tie strap extending between said jaws, means for securing the tie strap to the jaws, and a bar extending between and secured to said jaws having ears which are operatively associated with the tie strap

securing means to prevent accidental movement of the latter. 10

Signed at Chicago, State of Illinois, this 15th day of June, 1917.

FREDERIC H. BENDER.
